(57) **CLAIM**

The ornamental design of vehicle wheel and cap, as shown and described.

DESCRIPTION

FIG. 1 is a perspective view of the vehicle wheel and cap showing the new design;

FIG. 2 is a top down view thereof; and,

FIG. 3 is a side view thereof.

The broken line showing of the rear portion of the rim is included for the purpose of illustrating environment and forms no part of the claimed design.

1 Claim, 3 Drawing Sheets

FIG. 1

FIG. 2

FIG. 3
